UNITED STATES PATENT OFFICE.

JOHN H. PARSONS, OF WILMINGTON, DELAWARE, ASSIGNOR OF ONE-HALF TO WILLIAM H. SAVERY, OF WILMINGTON, DELAWARE.

APPARATUS FOR IMPREGNATING WOOD.

1,257,923.

Specification of Letters Patent. Patented Feb. 26, 1918.

Application filed November 11, 1916. Serial No. 130,725.

To all whom it may concern:

Be it known that I, JOHN H. PARSONS, a citizen of the United States, residing at Wilmington, in the county of Newcastle and State of Delaware, have invented certain new and useful Improvements in Apparatus for Impregnating Wood, of which the following is a specification.

This invention relates to an apparatus for 10 impregnating wood, such as railway ties or logs, with creosote or other substances, the primary object of the invention being to provide a device which is adapted for treating ties or logs under high pressure without injury to the fiber thereof, and in such 15 manner as to thoroughly impregnate the tie or log throughout and at the same time displacing therefrom all air, moisture, sap, etc., so that the pores of the wood will be 20 completely filled by the preservative fluid.

A further object of the invention is to 25 provide an impregnating apparatus which permits of the ready and convenient insertion and removal of the ties or logs, and the rapid clamping of the tie or log between a pressure piston and an abutment and the subsequent rapid release of the tie or log after treatment, thus allowing a maximum 30 number of logs or ties to be treated within a given period of time.

A further object of the invention is to 35 provide an impregnating apparatus which provides for a sealing contact between the pressure piston and abutment and the tie or log to prevent escape of the preservative fluid therearound, and the exposure of a portion of the tie or log held by the abutment to normal atmospheric pressure, so that the elements displaced from the pores 40 of the tie or log will be entirely forced out, thus insuring the full and complete impregnation of the log throughout its entire area.

A still further object of the invention is 45 to provide an impregnating apparatus of the character described in which the pressure piston employed is in the form of a floating piston movable in opposite directions by fluid pressure and gravity, and in which a novel construction and organization 50 of fluid supply and discharge connections is provided for supplying the preservative fluid under high pressure to the apparatus and discharging it therefrom.

With these and other objects in view, the 55 invention consists in the features of con-

struction and combination and arrangement of parts hereinafter more fully described and claimed, reference being had to the accompanying drawings, in which:

Figure 1 is a rear end elevation of a wood 60 impregnating apparatus embodying my invention, the foundation supports being omitted;

Fig. 2 is a longitudinal section through the cylinder, showing a railway tie held in 65 position to be treated, and showing the fluid pressure supply and exhaust devices in elevation;

Fig. 3 is a side elevation of the device 70 showing parts omitted in Figs. 1 and 2; and

Fig. 4 is a vertical longitudinal section through the cylinder of an impregnating apparatus designed particularly for treating a number of ties or logs at a time.

Referring now more particularly to Figs. 75 1 to 3, inclusive, of the drawings, 1 designates a cylinder or casing, which may be mounted with its axis in a horizontal plane, but, as shown in Fig. 2, is preferably mounted upon suitable supports 2 in an inclined 80 position, the rear end of the cylinder being disposed at a slightly lower level than the front end thereof, for a purpose hereinafter described. This cylinder or casing 1 is designed to receive the log or tie 3 which 85 is to be treated, and which in practice is disposed to bear at its outer end against an abutment 4 slidably mounted in a doorway or chamber 5 formed in the outer face of a head ring 6, riveted or otherwise suitably 90 fastened to the outer or rear end of the cylinder. This chamber or doorway 5 is closed at its outer side by a removable head 7 detachably fastened, as by means of bolts 8, to the head ring, said head 7 being provided 95 with an opening 9 for the insertion and removal of the tie, which opening is closed against the outward movement of the tie therethrough when the abutment 4 is in operative position. The abutment 4 is provided with a tapering passage 10 extending 100 entirely therethrough and communicating with the opening 9 when the abutment is in operative position, said passage 10 being of frusto-conical, frusto-pyramidal, or other 105 suitable form conforming to the cross sectional shape of the tie 3. The inner portion of said passage 10 provides a socket to receive the adjacent end of the tie, and is provided with a V-shaped shoulder 11 110

- against which the end of the tie abuts, and which shoulder serves as a sealing rib which is forced into the grain of the tie, to prevent the escape of the preservative fluid 5 around the end of the tie and through the passage, and also to permit of the ready release of the tie from the abutment 4 after being creosoted or otherwise treated. The abutment 4, which serves also as a closure 10 or door for the doorway or passage at the front end of the cylinder, is adapted to be raised and lowered out of and into operative position by suitable adjusting means, shown in the present instance as a rod 12 15 slidable through a stuffing box 13 at the top of the head ring and slidably and pivotally connected with an operating lever 14, whereby it may be raised and lowered in an obvious manner.
- 20 The tie 3 disposed within the cylinder 1 is clamped between the said fixed abutment 4 and a pressure piston 15 disposed within a guide 16 upon the rear end of the cylinder. This pressure piston 15 is in the form of a 25 floating piston, *i. e.*, a piston which is free from connection with any mechanical operating means, in order that it may be moved back and forth within the cylinder under opposing fluid pressures and gravity. The 30 forward end of this floating piston is provided with a socket 17 corresponding in shape to the passage 10 in the abutment 4 and also provided with an abutment shoulder 18 forming a sealing rib to sink into the 35 adjacent end of the tie and form a fluid-tight connection between the tie and piston. The rear portion of the socket 17 provides a fluid circulating pocket or chamber in rear of the engaged inner end of the tie, and 40 the socket as a whole is formed in a reduced portion 19 of the piston which is of less diameter than the body of the piston and the cylinder, so as to allow of the circulation of the fluid therearound, ports or passages 45 being formed in the walls of the socket to connect said pocket or chamber with the interior of the cylinder between the abutments, whereby the preservative fluid may be brought into contact with the clamped inner 50 end of the tie. The piston 15 is movable back and forth within the rear end of the cylinder to clamp or release the tie and may, therefore, be forced forward under the fluid pressure to engage the inner end of the tie 55 and clamp the outer end thereof within the socket of the abutment 4, or forced backwardly into the cylinder to release the tie so that the abutment 4 may be drawn upward or retracted to permit removal of the treated tie through the doorway and opening 9.
- 60 When the piston is forced forward to the position shown in Fig. 2 to engage an inserted tie 3 and clamp the same as described, the interior of the cylinder is separated by 65 the said piston into pressure chambers 21 and 22, the chamber 21 receiving fluid to force the piston forward into clamping position, and the chamber 22 in combination with the chamber 17 receiving fluid under pressure for the impregnation of the tie 70 therewith. The fluid is supplied to these respective chambers through pipes or conductors 23 and 24 having controlling and cut-off valves 25 and 26 arranged therein, which pipes are connected at a point between said valves with a supply pipe 27 leading from the outlet of a suction and force pump 28. The inlet of this pump is, in turn, connected by a pipe 29 with a tank or reservoir 30 containing the creosote or 80 other fluid, and this tank or reservoir is connected with a return pipe 31 leading thereto from the pipe 27 at a point between the pump and pipes 23 and 24. At the point of communication of the two pipes 27 and 31 85 is a cut-off or controlling valve 32, and arranged within the pipe 31 is a cut-off and controlling valve 33. A by-pass pipe 34 connects the pipe 27 between the pump and valve 32 with the pipe 31 between the tank 90 30 and valve 33 and is provided with a pressure regulating check valve 35 operated to permit flow of fluid through the pipe 34 from the pipe 27 to the portion of the pipe 31 between the tank 30 and valve 33, while 95 preventing flow of the fluid in the reverse direction. A controlling and cut-off valve 32' is also arranged in pipe 27 between the point of connection of pipe 34 with the pipe 27 and the valve 32. The by-pass pipe 34 is 100 designed to form with the pump, fluid tank and pipes 27, 29 and 31 a complete circuit for the flow of the fluid from the tank to the pump and back to the tank, so that the pump may be maintained in operation at periods 105 when the apparatus is temporarily inactive or inoperative as during periods while a tie is being inserted or removed. The by-pass pipe also serves as a safety connection to 110 prevent over supply of fluid or increase of pressure beyond the maximum within the treatment cylinder, the arrangement being such that when the pressure in the cylinder exceeds the forcing pressure in the pump, which is contained within safety limits, the 115 fluid will circulate back and forth between the tank and pump, as will be readily understood. For the purpose of indicating the pressures within the chambers 21 and 22, suitable pressure gages 36 and 37 are provided and, in addition, if desired, suitable safety or escape valves of any ordinary type or construction may be employed.
- 120 In the operation of the apparatus, a tie or log is inserted through the opening 9 and doorway 5 into the cylinder 1, and the abutment then moved downward by means of its operating mechanism into abutting position. The valves 26 and 33 are then closed and the valves 25 and 32 opened, and, the 125 130

pump being then set into action, the fluid will be forced under pressure through the pipe 23 into the chamber 21 and will force the piston 15 outwardly or toward the abutment 4 until it receives the inner end of the tie and forces the outer end thereof into the socket of the fixed abutment, the tie thus being clamped in position for treatment. The valve 26 is then opened and the preservative fluid is forced under pressure into the chamber 22, during which operation the valve 25 may be closed to maintain the pressure in the chamber 21 and as a result the preservative fluid in the chamber 22 will be forced under pressure into the tie and caused to thoroughly impregnate the same. It will be evident from the foregoing description that a portion of the fluid will pass through the ports 20 into the cavity 17, so that the pressure upon the rear end of the tie will be the same as that to which the body of the tie is exposed in the chamber 22, but it will be noted that the outer end of the tie will be exposed through the outer end of the passage 10 and the opening 9 to the atmosphere, the result being that the fluid penetrating the pores of the wood will force all of the contained moisture or other contents out at the exposed end of the tie, the discharged substances together with any of the fluid which may escape therewith, passing out at the opening 9 and being received into a funnel or catch basin 38 and discharged therefrom into a suitable receptacle 39 having a drain pipe 40, through which the preservative fluid may be withdrawn or caused to flow back in any suitable manner to the tank 30 for further and continued use. As soon as the tie has been fully treated, the valve 26 is closed and the valves 25 and 33 are opened, thus maintaining the pressure within chamber 22 while relieving the pressure behind the piston 15 within the chamber 21, whereupon the fluid within the chamber 22, being under higher pressure, will force the piston 15 backward, thereby releasing the tie 3. Then the valve 32' is closed, the valves 25, 32 and 33 are opened, and then the pressure of the creosoting fluid will leave chamber 21, as the valve 32' closes the pump line. The valves 25 and 26 are then closed, after which the fluid contained in the chamber 22 may be drained off in any suitable manner until the level of the fluid at the forward end of the cylinder is just below the line of the doorway 5. The abutment 4 is then elevated and the treated tie removed through the doorway and opening 9 and another tie inserted in its place, if the operation is to be continued, the tie being clamped and treated in the manner heretofore described. It will be evident that by the use of the inclined cylinder 1 it will not be necessary to drain off the entire amount of fluid contained within the cylinder on opposite sides of the piston 15 in order to place the apparatus in condition for discharging and recharging operations, since a portion of the fluid may remain in the forward end of the cylinder with advantage, much less time being required under such conditions to reprime the cylinder for further operation. As the cylinder 1 is inclined downwardly from its front to its rear end, the backward movement of the piston 15 will be facilitated by the action of gravity as well as the pressure of the fluid in the chamber 22. It will be evident that as the piston 15 is free for back and forth motion under opposing pressures, and that as the abutment 4 may be conveniently moved into and out of operative position, provision is made for rapidly inserting and removing and clamping and releasing the tie and subjecting it to treatment, thus reducing the amount of time and labor required in treating a number of ties and enabling a larger number of ties to be treated within a given period, with resultant economy.

It will be understood that the purpose of the movable piston 15 is to jam the end of the tie against the fixed abutment 4 and to take care of the varying lengths of ties that are to be treated. This piston is made to fit the cylinder so that a high degree of pressure, say 1,500 pounds, may be applied in the chamber 21 between said piston and the rear wall of the cylinder. Such amount of pressure will force the piston forward and jam the tie tightly against the abutment 4, so that the preservative liquid under a determined pressure, say 750 pounds, may be admitted into the chamber 22 and cavity 17 of the piston 15, the fluid under this degree of pressure being adapted to thoroughly penetrate the tie and to force out the sap and other like substances contained therein, the fluid filling the pores of the wood and thus saturating the tie in a thorough and complete manner with the preservative agent. It will be observed that the fluid admitted under pressure into the chamber 22 will pass through the ports 20 into the cavity 17 and subject the inner end of the tie to pressure within the space bounded by the sealing projection 18, as a result of which practically the entire area of the tie, except that portion of its outer end exposed to the atmosphere at the opening 9, will be subjected to the force of the fluid pressure within the chamber 22. This amount of fluid pressure acting upon the surface of the tie will be sufficient to support the tie and hold it jammed against the abutment 4 irrespective of the pressure of the piston 15, so that if desired, as soon as the tie is subjected to the full amount of the pressure in the chamber 22 and cavity 17, the pressure contained within the chamber 21 may be released or exhausted, allowing the movable piston 15 to move forward and release the tie.

to move backward and out of engagement with the tie, thus obviating the necessity of maintaining a high pressure within the chamber 22 and also obviating the actual necessity of the sealing projection 18 being held directly in contact, after the initial jamming action with the tie, in order to support the tie in position while it is being treated. This result or action is due to the fact that, a portion of one end of the tie is exposed to atmospheric pressure, while substantially the entire remaining area of the tie is exposed to the 750 pounds pressure in the chamber 22, which may be explained as follows: A standard tie, measuring 7" x 8" at each end = 56 square inches, when subjected to the pressure of 750 pounds per square inch, will be exerted at its inner end to a forcing pressure equal to the area of such end, viz. 56 square inches $\times$ 750 pounds = 42000 pounds or 21 tons total pressure. At its exposed end it may be assumed that an area 4 x 5 inches is exposed to the atmosphere, or 20 square inches $\times$ 750 pounds = 15000 pounds, which deducted from the 42000 pounds general pressure leaves 27000 pounds representing the force of pressure which holds the tie tight against the abutment 4 while being creosoted. Thus it will be apparent that the tie will be first jammed against the piston 15 to seal the opening 9 by the pressure behind the said piston 15, and that upon admitting fluid pressure to the chamber 22 such pressure flowing through the ports 20 into the cavity 17 will admit to the inner end of the tie a pressure equal to that which surrounds the body of the tie within the cylinder, the tie will thus be held positively in position, under pressure, even if the piston is not actually in contact with the end of the tie, so that a variation of pressures in the two chambers 21 and 22 may be employed without liability of the tie moving out of position and unsealing the opening 9 during the creosoting process.

In the use of the apparatus, which is primarily designed for creosoting railroad ties, but may be employed for suitably treating other logs of wood, it will be seen that an apparatus of a simple type is provided which may be either of stationary or portable type, and if portable may be mounted upon a railroad car for transportation from place to place where ties are to be treated. In practice, the pump may be driven by any suitable type of motor and if desired a single pump may be employed for supplying fluid to a plurality of devices so that a number of ties may be separately treated in individual devices at a time.

One or more grooves 5' may be provided in the rear wall of the chamber 5 to permit the fluid which is forced into said chamber 65 to drain back into the cylinder when the

abutment 4 is moved upwardly to retracted position.

In Fig. 4 I have shown a modified form of my invention in which the construction is substantially the same as that previously described and the principle of operation the same, but in which provision is made for treating a plurality of ties or logs within a single apparatus at one time. In this construction of device, the cylinder 1^a will be made of proper diameter and the heads and head rings secured in the same general manner to the ends of the cylinder, but, as shown, the head 6' is provided with a cylindrical extension 41 divided by a partition 42 into a pair of compartments, within each of which may be arranged a piston 15^a of the character described, which may be either a single piston or a double piston, accordingly as it is desired to adapt the device for treating a single tie in either compartment or for treating two ties in either compartment simultaneously. These pistons are independently movable to clamp ties of different lengths, and are adapted for co-operation with an equivalent number of abutments 4^a, movable in a door or guideway 5^a which extends equidistantly above and below the axis of the cylinder. These abutments 4^a are independently adjustable into and out of operative position by means of separate and independent controlling devices of the construction previously described. As shown, a rod 43 may extend from the partition 42 outwardly between the closed abutments 4^a to form a stop to limit the closing movement of said abutments, and the free end of this rod may pass through a web 44 upon the outer head 7^a and be threaded to receive a clamping nut 45, to assist in holding said head in position and to further reinforce the partition, as will be readily understood. The apparatus in this multiple type of construction may be arranged either horizontally or in an inclined position, as desired, and suitable piping is provided for supplying pressure to the respective chambers 21, which are in communication with each other, so that fluid pressure may be supplied from a single reservoir and set of pipe connections.

While the device is herein shown as arranged in a horizontal position, or substantially horizontal position, for use, it is to be understood that it may also be employed in a vertical position.

I claim as my invention:

1. In an apparatus for impregnating wood with fluid under pressure, a cylinder, an abutment at one end of the cylinder, a piston slidably mounted within the cylinder for movement toward and from the abutment, and means for supplying the fluid under pressure to the interior of the cylinder.

- der for direct action on opposite sides of said piston.
2. In an apparatus for impregnating wood with fluid under pressure, a casing, an abutment within the casing, a movable member within the casing for clamping the article to be treated against said abutment, said movable member comprising a normally free floating piston movable into and out of clamping position by fluid pressure, and means for supplying fluid pressure to the cylinder on opposite sides of said piston.
3. In an apparatus for impregnating wood with fluid under pressure, a cylinder having a door way at one end for the insertion and removal of the article to be treated, an abutment movable laterally into and out of line of said door way and having an opening to expose a portion of the article abutting thereagainst to the atmosphere, a piston movable toward and from the first named abutment, and means for supplying the fluid under pressure to the cylinder on opposite sides of said piston.
4. In an apparatus for impregnating wood with fluid under pressure, a cylinder, an abutment within the cylinder, a piston movable toward the abutment and coöperating therewith for clamping the article to be treated, said abutment and piston having sockets therein to receive the ends of the article and embedding projections within said sockets to form a fluid tight sealing connection between the same and the ends of the article, the said piston being provided with ports connecting the sockets therein with the interior of the cylinder, and means for supplying fluid under pressure to the cylinder.
5. In an apparatus for impregnating wood with fluid under pressure, a cylinder, an abutment within the cylinder, a piston within the cylinder and movable toward and from said abutment, and means for supplying the fluid for action on the material to be treated under pressure at will to the interior of the cylinder between said abutment and piston, and to the interior of the cylinder between one end thereof and the said piston.
6. In an apparatus for impregnating wood with fluid under pressure, a cylinder, an abutment, a piston movable toward and from said abutment, pipes for supplying the fluid under pressure to the interior of the cylinder in front and rear of the piston, and valves for controlling the flow of the fluid through the respective pipes.
7. In an apparatus for impregnating wood with fluid under pressure, a cylinder, an abutment, a piston movable toward and from said abutment, a supply pipe for supplying the fluid under pressure, conducting pipes leading from said supply pipe and communicating with the interior of the cylinder at points in front and rear of the piston, and controlling valves in said conducting pipes.
8. In an apparatus for impregnating wood with fluid under pressure, a cylinder, an abutment, a piston movable toward and from said abutment, a reservoir for the fluid, a pump in communication at its inlet side with said reservoir, a supply pipe leading from the outlet of the pump, and valved conductors leading therefrom and communicating with the cylinder at points in front and rear of the piston.
9. In an apparatus for impregnating wood with fluid under pressure, a cylinder, an abutment, a piston movable toward and from said abutment, a reservoir to contain the fluid, a pump, a flow connection between the reservoir and the inlet of the pump, a valved supply pipe leading from the outlet of the pump, valved conductors connecting the supply pipe with the cylinder at points in front and rear of the piston, a return pipe leading from the supply pipe back to the reservoir, and a pressure-regulating valved by-pass pipe connecting the supply pipe with the return pipe.
10. In an apparatus for impregnating wood with fluid under pressure, a cylinder, an abutment having a socket to receive one end of the log or tie to be treated, said socket being in communication at its outer side with the atmosphere, a piston having a socket to receive the opposite end of the tie or log to be treated and having a cavity communicating with said socket and with the interior of the cylinder, and means for moving said piston toward and from the fixed abutment.
11. In an apparatus for impregnating wood with fluid under pressure, a cylinder having a doorway at one end thereof, an abutment movable into and out of alignment with said doorway and having a socket therein to receive one end of the log or tie to be treated and a passage for exposing such end of the log or tie to the atmosphere, a piston having a socket to receive the opposite end of the log or tie, and means for supplying fluid under pressure to the interior of the cylinder at points in front and rear of the piston.
12. In an apparatus for impregnating wood with fluid under pressure, a cylinder inclined from front to rear thereof, an abutment at the front end of the cylinder, means for moving the same into and out of operative position, a floating piston at the rear end of the cylinder movable forwardly under fluid pressure and rearwardly under the combined force of fluid pressure and gravity, and means for supplying fluid pressure to the cylinder on opposite sides of the piston.
13. In an apparatus for impregnating wood with fluid under pressure, a cylinder,

an abutment therein, a compound floating piston for coöperation therewith, said abutment having a series of log or tie engaging surfaces and said movable abutment 5 consisting of a series of independently movable piston members, and means for supplying fluid pressure to the cylinder on opposite sides of the piston member.

14. In an apparatus for impregnating 10 wood with fluid under pressure, a cylinder, an abutment within the cylinder, a piston coöoperating with said abutment for clamping the article to be treated between them, said piston being movable toward and from 15 the abutment and provided with a socket to receive the end of the article engaged thereby, a cavity communicating with said socket, and ports connecting said cavity with the interior of the cylinder, and means for supplying fluid pressure to the cylinder.
15. In an apparatus for impregnating 20 wood with fluid under pressure, a cylinder for confining the wood, an abutment having an opening therein to expose a portion of the

surface of the wood to the atmosphere, a piston 25 provided with a surface for sealing engagement with the wood and a cavity in communication with the cylinder for subjecting the portion of the wood bounded by the sealing surface to the pressure of the 30 fluid within the cylinder, and means for supplying fluid under pressure to the cylinder.

16. In an apparatus for impregnating 35 wood with fluid under pressure, a cylinder, an abutment, a piston for clamping the article against the abutment, means for supplying fluid to the cylinder on opposite sides of the piston, and means for varying the pressure of the fluid within the cylinder on 40 opposite sides of the piston.

In testimony whereof I affix my signature in presence of two witnesses.

JOHN H. PARSONS.
